UNITED STATES PATENT OFFICE.

JOHN H. GAULT, OF PHILADELPHIA, PENNSYLVANIA, ASSIGNOR TO THE HERO FRUIT JAR COMPANY, OF SAME PLACE.

DESIGN FOR A BOTTLE-STOPPER.

SPECIFICATION forming part of Design No. 24,577, dated August 20, 1895.

Application filed April 4, 1894. Serial No. 506,352. Term of patent 14 years.

To all whom it may concern:

Be it known that I, JOHN H. GAULT, a citizen of the United States, residing in Philadelphia, Pennsylvania, have invented a certain Design for Bottle-Stoppers, of which the following is a specification.

My design for a bottle-stopper is clearly shown in the accompanying drawings, and the main feature of my design is the cap 10 formed to represent a flower of the buttercup type and having an ornamental flange.

Referring to the drawings, Figure 1 is a perspective view of a bottle-stopper, illustrating my design. Fig. 2 is a plan view. Fig. 3 15 is a side view.

A is the flange of the bottle-stopper, having an ornamental band consisting of a series of foliated scrolls and ribbon-work, and projecting from this flange is a stem B, supporting a

representation of a buttercup having petals 20 *d*, curved upward, and stamens and pistils *e* at the center below the upper edge of the petals. *f* are cavities near the center of the flower.

I claim—

The design for a bottle stopper a flange with a band having foliated ornamentation and a stem having an ornamental head in the shape of a buttercup as herein described and as shown in the accompanying drawings. 25 30

In testimony whereof I have signed my name to this specification in the presence of two subscribing witnesses.

JOHN H. GAULT.
